DENTAL MEDICAMENT BOTTLE STAND FOR DENTAL BRACKET TRAYS

Chester B. Rackson, Hicksville, N.Y.

Application December 26, 1957, Serial No. 49,029

Term of patent 14 years

(Cl. D24—1)

FIG. 1.

Fig. 2 is a bottom perspective view.

The broken line representation of a dental bracket tray in Fig. 1 is for illustrative purposes only.

I claim:

The ornamental design for a dental medicament bottle stand for dental bracket trays, substantially as shown and described.
